TELEGRAPH SIGNALING SYSTEM.

Application filed March 15, 1920. Serial No. 365,935.

To all whom it may concern:

Be it known that we, JOHN M. FELL and RALPH E. PIERCE, residing at Hackensack and Larchmont, in the counties of Bergen and Westchester and States of New Jersey and New York, respectively, have invented certain Improvements in Telegraph Signaling Systems, of which the following is a specification.

10 This invention relates to telegraph signaling systems and particularly to means for preventing the undesirable reaction between the polar relays of a duplex system when a receiving operator opens his key in order 15 to get control of the circuit.

One of the most common faults found in operating duplex sets on a half duplex basis is the mutual reaction between the transmitting and receiving relays of the duplex set. 20 This reaction occurs when an operator who is receiving signals from another station at the other end of the circuit opens his key in order to get control of the circuit. This reaction manifests itself in a chattering or 25 buzzing of the relays arising from the vibration of the armatures of the relays between their respective marking and spacing contacts when the transmitting keys at opposite ends of the line are simultaneously in 30 the open position. In the standard polar duplex set this fault is remedied by means of a back contact repeating sounder operated by a pole changer which closes the receiving circuit whenever the pole changer 35 is open irrespective of whether or not the circuit is closed at the receiving relay. The set is thus locked against the said mutual reaction. Our invention is particularly related to a circuit of the type disclosed in the 40 copending application of J. M. Fell, Serial Number 365,911, filed March 15, 1920, which provides for the use of polar relays as transmitting pole changers. It is the object of our invention to provide a simple 45 and effective means to prevent the reaction between the relays shown in the Fell circuit, thereby improving the "breaking" operation so as to enable a receiving operator to get control of the circuit promptly, thus 50 improving the general efficiency of the service.

Other and further objects of this invention will appear from the following descrip-

tion when read in connection with the attached drawing which shows one form of 55 its embodiment.

In the drawing X and Y represent two repeater stations which are joined by the line circuit L₂. At the stations X and Y are terminated the loop circuits L₁ and L₃ 60 respectively, which serve to connect the telegraph substations A and B respectively with the said repeater stations. At substation A the equipment comprises a key K₁, a relay R₅, a sounder S₅, and a source of direct current, B₅, the polarity of which is opposite to that of battery B₃, associated with relay R₂, at station X. At substation B the equipment is similar, comprising a key K₂, a relay R₆, a sounder S₆, and a battery B₁₀, the polarity of which is opposite that of battery B₅ associated with the relay R₃ at station Y. Although the equipment at stations A and B is represented as being of the simple Morse type, it is to be understood that the invention 75 is not limited to the use of this particular type of apparatus at the substations but that any of the well known types of telegraph station apparatus may be used.

The equipment at each repeater station 80 embraces a group of two polar relays having polarized sounders connected in a leak circuit from the armatures to ground and having the usual artificial lines adapted to balance the circuits connected with the said 85 polar relays. Thus at station X, R₁ and R₂ represent two polar relays each having two windings connected differentially. The windings 1 and 2 of relay R₁ are connected respectively with the loop circuit L₁, and with the artificial line AL₁. The midpoint, or apex of the said windings is connected with the armature of the polarized sounder S₁, the windings of which are connected in a leak circuit from the armature of relay R₁ 90 to ground. Windings 3 and 4 of relay R₂ are connected respectively with the line circuit L₂ and with the artificial line AL₂. The apex of these windings is connected, with the armature of relay R₁. The armature of relay R₂ is connected with the normal contact 9, of the sounder S₁, and the said armature is also connected through the windings of polarized sounder S₂ to ground. The other contact 10, of the sounder S₁ is connected with the marking battery 105

B₃. Associated with the relays R₁ and R₂ are the marking batteries B₁ and B₃ respectively and the spacing batteries B₂ and B₄ respectively. The equipment at the repeater 5 station Y is similar to that at station X, comprising the polarized relays R₃ and R₄ having windings 5-6 and 7-8 respectively. Also associated with these relays are the 10 artificial lines AL₃ and AL₄ and the sounders S₃ and S₄ respectively. Marking batteries B₅ and B₇ and spacing batteries B₆ and B₈ are associated with the contacts of 15 the armatures of relays R₃ and R₄ respectively.

Having in mind the foregoing description 15 of the parts of the apparatus comprising the circuit in which this invention is embodied, the invention will be clear from the following description of the mode of operation 20 of this circuit.

Let it be assumed that station A is transmitting signals and that station B is receiving signals. That is to say, that key K₁ is being closed and opened to transmit marking and spacing signals and that key K₂ remains closed for the reception of the 25 transmitted signals. Since batteries B₉ and B₃ are of opposite polarity, the closing of key K₁ will cause current to flow over a circuit comprising battery B₉, relay R₅, key K₁, loop L₁, winding 1 of relay R₁, contact 30 9 of sounder S₁, marking contact of relay R₂ and battery B₃ to ground. Current will also flow through winding 2 and artificial 35 line AL₁ to ground. The difference in value and direction of the currents in windings 1 and 2 will be such as to hold the armature of relay R₁ upon its marking contact. Since batteries B₁ and B₇ associated with relays R₁ and R₄ respectively are opposed to each 40 other no current will flow through the line L₂ or through windings 3 and 5 of relays R₂ and R₃ respectively. Current flowing in windings 4 and 6 of the said relays will 45 maintain the respective armatures upon their marking contacts. Since batteries B₅ and B₁₀ are in conjunction, current will flow over the line L₃ and produce a marking signal at the substation B. If a spacing 50 signal is transmitted from station A to station B no current will flow through winding 1 of relay R₁ and in consequence thereof the armature of this relay will be moved to its spacing contact as the result of the 55 current in the winding 2. This results in the connection of the battery B₂ to the line L₂ and since B₂ and B₇ are in conjunction current will flow through the line L₂ and the windings connected thereto. Current 60 will also flow in windings 4 and 6 of relays R₂ and R₃ respectively. The difference in value and direction of the currents in windings 3 and 4 will hold the armature of relay R₂ upon its marking contact. The difference 65 in value and direction of the currents in windings 5 and 6 will move the armature of relay R₃ to its spacing contact. This results in the connection of the battery B₆ to the line L₃ and since B₆ and B₁₀ are opposed to each other no current will flow through the said line. In consequence thereof the spacing signal transmitted from substation A will be received at station B. It is desirable to point out that the sounders S₁ and S₃ respond to the transmission of signals 70 from station A to station B. Sounders S₂ and S₄ respond to the transmission of signals from station B to station A. Thus when a marking signal is being sent from A to B the armature of S₁ will remain on contact 9 and that of S₃ on its marking contact. The transmission of a spacing signal from A to B moves the armature of S₁ to contact 10 and that of S₃ to its corresponding spacing contact. Sounders S₂ and S₄ 75 operate in a similar manner when signals are transmitted from B to A.

Let it be assumed now that when station A is transmitting a spacing signal the operator at station B opens his key K₂ for the purpose of getting control of the circuit. By the opening of key K₂ the armature of relay R₁ will be moved to its spacing contact as a result of the flow of current from battery B₈. Since key K₂ is opened at the 80 same instant the armature of relay R₄ will be moved to its spacing contact as the result of the flow of current from battery B₅. Since now batteries B₂ and B₈ are opposed to each other no current will flow in the line L₂ or windings 3 and 5 of relays R₂ and R₃ respectively, and the flow of current in windings 4 and 6 respectively will be in 85 such direction as to move the respective armatures to their spacing contacts. Considering repeater station X the flow of current from battery B₄ through winding 2 would be in such direction as to tend to move the armature of relay R₁ to its marking contact if contact 9 remained closed. However, when the armature of relay R₁ is 90 on its spacing contact, the polarized sounder S₁ is operated and the apex of windings 1 and 2 of relay R₁ is connected through the armature of sounder S₁ and contact 10 to battery B₃. The flow of current through the winding of relay R₁ is then in such direction as to hold its armature on its spacing contact. The operation of sounder S₄ 95 at station Y acts in a similar manner to prevent the movement of relay R₄. By means of this invention the buzzing or chattering of the polar relays resulting from the vibration of their armatures between their respective contacts when both keys are open is prevented by the interposition of the polarized sounder or equivalent switching means which reverses the polarity of the current flowing through the windings 100 of one of the relays. Heretofore in duplex 105

circuits in which no special preventive means were employed this buzzing would continue until the armatures had swung sufficiently out of phase to rest simultaneously upon contacts of opposite polarity. Our invention provides positive means for changing the polarity of the windings when conditions which are capable of producing such undesirable reaction have arisen.

10 Another object of our invention is to prevent the interference by incoming signals with a spacing signal transmitted for the purpose of obtaining control of the circuit. For example, if station A is sending signals to station B and the key K_2 at station B is opened to get control of the circuit, the reception of the signal at repeater station Y, corresponding to the closing of key K_1 , will cause relay R_3 to connect battery B_5 through its armature and the armature of sounder S_4 to the apex of windings 7 and 8 of relay R_4 . Since key K_2 is opened in order to get control of the circuit, no current will flow in line L_3 , and the direction of current in winding 8 will be such as to operate relay R_4 , moving its armature to its spacing contact. This serves to connect battery B_3 to the armature of relay R_4 and operates the sounder S_4 which connects battery B_5 to the apex of windings 7 and 8 of relay R_4 over a circuit which avoids the contacts of relay R_3 . If a spacing signal is now received at repeater Y over line L_2 , the relay R_3 will have a spacing battery connected to its armature, but the connection between this armature and the apex of the windings 7 and 8 of relay R_4 is broken at the contacts of the polarized sounder, and in consequence, the armature of relay R_4 remains on its spacing contact. If this connection had not been broken the spacing current from battery B_6 would have passed through winding 8 of relay R_4 in such direction as to move its armature to its marking contact, and a marking signal would have been sent from this relay instead of a spacing signal, corresponding to the open position of key K_2 . It will be seen, therefore, that by using a polarized switching device such as the sounder S_4 , the interference by incoming signals with the "break" operation is thereby avoided.

Although this invention has been disclosed in a particular form in which a polarized sounder, connected into a leak circuit from the armature of a polar relay, serves to prevent the interference heretofore described, it is to be understood that a relay may be substituted for the said sounder, or that the function of the sounders may be performed by relays connected in the loops L_1 and L_3 in series with said polar relays, or by other and different arrangements without departing from the spirit and scope of the appended claims.

What is claimed is:

1. In a telegraph signaling system, the combination with two line circuits of two polar relays, each individual to a line circuit and each having an artificial line designed to balance its respective line circuit, sources of potential of opposite polarity connected with the contacts of each relay, means to connect the armature of each relay with the midpoint of the winding of the other relay, one of the said connections including the armature and one contact of a polarized sounder having its winding connected with the armature of the other of said relays and having its other contact connected with one of the sources of potential to reverse the polarity of the current applied to the midpoint of the winding of one relay when spacing signals are being sent simultaneously from both ends. 70 75 80 85

2. In a telegraph signaling system, the combination with two line circuits of two polar relays, each individual to a line circuit, one terminal of each winding being connected with its line circuit and the other with an artificial line, sources of potential of opposite polarity connected with the marking and spacing contacts of each of said relays, means to connect the midpoint of the winding of one relay with the armature of the other relay, means to connect the midpoint of the winding of the said other relay with the armature of the said first mentioned relay, the said latter connecting means including the armature and one contact of a polarized switching means, the winding of which is connected with the armature of the said other relay. 90 95 100

3. In a telegraph signaling system, the combination with two line circuits of a repeater comprising two polar relays and polarized switching means, one winding of each of said relays being connected with one of said line circuits and the other winding of each relay with an artificial line, the midpoint of the windings of one relay being connected with the armature of the second relay, and the midpoint of the windings of the said second relay being connected with the armature of polarized switching means having one of its contacts connected with the armature of said first mentioned relay and its second contact connected with the marking battery of said first mentioned relay, said switching means being located in a leak circuit between the armature of said second relay and ground and controlled by said second relay whereby the polarity of the current applied at the midpoint of the windings of said second relay may be reversed when both line circuits are transmitting spacing signals. 105 110 115 120 125

4. In a telegraph signaling system, the combination of two repeaters, each comprising two polarized relays having the 130

armature of each relay of a repeater connected with the windings of the other relay of said repeater, a line connecting the said repeaters, a loop circuit connected with each repeater, and means associated with each repeater to maintain the armature of one of the relays of a repeater upon its spacing contact regardless of the change of position of the armature of the other relay whenever spacing signals are simultaneously transmitted from the stations of both loop circuits.

5. In a telegraph repeater, the combination of two polar relays, each having a plurality of primary and secondary windings, the junction point of the primary windings

of one relay being connected with the armature of said second relay, and the junction point of the primary windings of said second relay being connected with the armature of a polarized sounder, one of the contacts of which is connected with the armature of said first mentioned relay, and the other contact directly connected with the marking battery of said first mentioned relay, the said sounder being controlled by the vibrating circuit of said second relay. 20 25

In testimony whereof, we have signed our names to this specification this 12th day of March, 1920.

JOHN M. FELL.
RALPH E. PIERCE.
